UNITED STATES PATENT OFFICE.

ISAAC DE HAVEN, OF ALLEGHENY, PENNSYLVANIA.

DESIGN FOR A STOVE.

SPECIFICATION forming part of Design No. 22,220, dated February 14, 1893.

Application filed December 22, 1892. Serial No. 456,098. Term of patent 3½ years.

To all whom it may concern:

Be it known that I, ISAAC DE HAVEN, residing at Allegheny, in the county of Allegheny and State of Pennsylvania, have invented and 5 produced a new and original Design for Stoves, of which the following is a specification, reference being had to the accompanying drawings, in which—

Figure 1 represents a perspective front view 10 of my design. Fig. 2 is a view illustrating the design of the top.

The leading features of my design are the ornamental representations, on the top A, the name plate B, the hood C, pilasters D, base 15 and legs E and F, the blower G and the front H.

A indicates a representation of the stove top, A' a raised panel like portion, the center of which has a circular representation a' to each side of which is a floral ornamentation 20 a''. Surrounding the front edge of such panel A' is a scroll like ornamentation a''' which terminates at the ends in a square or tile like representation a'''.
The representation of the name plate in- 25 cludes a central frosted portion b and ornamental end portions b'' on which are delineated two figures b' b'' one above the other sur- rounded by scroll like ornamentations b'' b'''.

The ornamental hood representation C, is 30 formed of a central arabesque c, from which extend in opposite directions scroll ornaments c' c''. The pilaster ornamentations, comprise a frosted like base d, surrounded by corrugated like edge ornamentations d' a central floral

ornament d'' and the transverse border like 35 ornaments d'''.

The representation of the front frame in- 40 cludes a central panel portion H, having dia- mond like figures h in which are floral orna- ments h', the horizontal corrugated represen- 45 tations h'' and an upper border or frieze h''. The ornamental base edge is represented by a series of semi-circular figures e.

f indicates a circular ornament on the up- 45 per part of the leg in which is a central orna- ment f', laterally extended ornaments ter- minating in pointed like portions f'', being also delineated on such leg.

On the blower, G indicates a panel like rep- 50 resentation in the ends of which are scroll ornaments g, which terminate at vertical bead like portions g', adjacent which are frosted portions g'' between which is a representation of a slide door g''' which has floral ornamenta- 55 tions g'''' on its face and over which is a representation of an ornamental handle g''''.

What I claim is—

1. The design for stoves substantially as herein shown and described.
2. In the design for a stove, the top, sub- 60 stantially as herein shown and described.
3. In a stove, the design for a blower sub- stantially as herein shown and described.

ISAAC DE HAVEN.
